Fig. 4.

Fig. 5.

FIG. 1 is a perspective view of a storage module embodying the design and including a drawer therein.

FIGS. 2, 3 and 4 are respectively front, top and side views of the storage module of FIG. 1.

FIG. 5 is a perspective view of the storage cabinet or similar article of FIG. 1, wherein the drawer has been omitted for convenience of illustration.

The dominant feature of the design is characterized by the housing portion of the storage cabinet or similar article, namely, the box-like structure with the relatively small band around the mid-section thereof, as best illustrated in FIG. 5.

I claim:

The ornamental design for a storage cabinet or similar article, as shown and described.
